UNITED STATES PATENT OFFICE.

BENJAMIN OTTO FANSLOW, OF LOS ANGELES, CALIFORNIA, ASSIGNOR, BY DIRECT AND MESNE ASSIGNMENTS, TO THE UNIVERSAL POLYGRAPH COMPANY, (INCORPORATED), A CORPORATION OF ARIZONA TERRITORY.

REPRODUCING AND IMITATING MACHINE.

No. 873,930.

Specification of Letters Patent.

Patented Dec. 17, 1907.

Application filed December 3, 1906. Serial No. 346,186.

To all whom it may concern:

Be it known that I, BENJAMIN OTTO FANSLOW, of the city of Los Angeles, in the county of Los Angeles, in the State of California, have invented a Reproducing and Imitating Machine, of which the following is a full, clear, and exact specification, reference being had to the annexed drawings, and to the figures and letters marked thereon.

10 My said invention which relates to a new or improved machine for reproducing copies of documents, drawings, and pictorial representations, has for its object to effect such reproduction by printing operations as hereinafter described.

The machine constituting my present invention, consists of a flat stationary base, upon or in which, there is carried either printing type, or other body having upon its 20 upper surface the reproduction of any drawing, writing, or pictorial representation in the state capable of producing impressions from. In the parallel edges or opposite sides of this flat stationary base, parallel 25 grooves which may be of various transverse sectional shapes are situated, and in these grooves the engaging parts of a movable carriage which contains the impression roller are retained in permanent operative relationship as hereinafter described.

The movable carriage and the impression roller are traversed from end to end of their distance of movement, in successive alternations of direction of these movements, 35 that is to say, to and fro through any period of use of the machine for reproducing any required number of copies of documents, drawings, or other representations, and the ends of the impression roller axle have 40 mounted thereon two spur wheels, which respectively gear into two spur teeth racks running lengthwise of the body of the machine, and operating as hereinafter described. The impression roller axle of the machine is 45 provided with a crank handle for operating it, or it may be operated by a driving pulley and belt, or by equivalent driving gear. The arrangement of the machine otherwise, is generally such that it may be operated 50 rapidly, with ease, certainty and economy, in the production of fac-simile copies of original documents, drawings, or other representations.

Upon the annexed drawings, Figure 1, is a

side elevation of the reproducing machine 55 constituting my invention. Fig. 2, is a plan of the same. Fig. 3, is a transverse section on the line 3, 3, Fig. 1. Fig. 4, is a vertical cross section showing the means of raising or lowering, and in general adjusting the level 60 or horizontal position of the type bed, or its equivalent, containing or holding the printing surface, other than that of type. Fig. 5, is a plan corresponding to Fig. 4.

In Figs. 1, 2, 3, 4, and 5, the horizontal portion is marked A, and it is shown as consisting of a flat frame of cast iron within which is contained a flat plate X, whose upper surface is planed level. Upon this plate X, the types B, are carried in a chase, whose side and end portions are marked C, and wherein the types B, as shown are retained in the operative condition by being held in the chase C, by reason of the furniture D, D, of the chase, being forced in the well known manner against the type slips E, and types B, by the toothed wedges F, and G, respectively, all as more especially shown in Figs. 2, and 5, or when a printing block or other printing surface is used other than types, then the said printing block is held within the chase C, and adjusted therein upon the plate X, in proper relationship with the inking ribbon and impression roller. The wedges F, and G, for tightening or loosening the furniture D, D, the types B, 85 and type slips E, are operated by the insertion of the teeth of a galley key between the teeth on the inner faces of the wedges F, and G, when by turning the galley key in the manner well understood, and as commonly used, the wedges F, and G, are pressed against the furniture D, D, or withdrawn therefrom, thus holding the types B, and type slips E, firmly in the chase C, or releasing them therefrom as is well understood by the operation 90 of a galley key, which does not constitute any part of my present invention, and is therefore not shown in the drawings. The chase C, and its contents, namely, the furniture D, D, the types B, and the type slips E, when resting on the flat bottom of the adjustable base X, are held in place by the thumb nuts and bolts I, and I', respectively, shown at Figs. 2, 4, and 5, by which the adjustment of the chase C, and its contents to their proper situation upon the base X, is from time to time effected as is well understood.

When instead of printing from a surface of

type which may be either type in style and character corresponding to that commonly used in typewriting machines, or which may be of other kinds of type such as type in imitation of script, or of other form or character, or when copies of drawings, pictorial representations or maps are to be made in the machine constituting my invention, then, instead of using the chase and its equipment as hereinbefore described; a block of material such as type-metal, or other metal, a wood or metal engraving, electrotype, or other block containing on its upper surface the depiction to be reproduced by a printing operation is carried and held in place, either by the thumb nuts or bolts I, and I', or fastened thereto, that is to say, upon the base X, by any equivalent means.

At each side of the base A, is a rectangular space J, throughout the entire length of the base A. In the projecting part of the base there is cut a V-shaped groove K, as shown at Fig. 3, the purpose of which is hereinafter explained.

The carriage of my new or improved machine consists of the frames L, which are securely fastened together at the top by the bridge M, the ends of which are fastened to the two frames L, respectively, by the screws N, N, N, N. The lower part of each frame L, is bi-furcated as shown at Figs. 1, 2, and 3, and at the end of each bi-furcated arm there is carried a stud O, upon the inner end of which there is also carried rotatively, the roller P, whose form and construction is more especially shown in Fig. 3, and its position indicated in dotted lines in Fig. 1. These rollers P, press up into and against the surface of the grooves K, and conjointly with the upper rollers U, which bear upon the top of the surfaces of the rail t, maintain the carriage consisting of the end frames L, and the bridge M, also the impression roller Q, in proper operative relationship with the base A, and with the type or other printing surface, and the printing ribbon, also the paper l to be printed upon; in such manner that the carriage and the parts of the mechanism carried thereby cannot be dislocated from their proper relationship to and with the base A, either accidentally, or in any other manner than by taking asunder some of the parts for admitting of the separation when required, of the carriage and its connections on the base A, of the machine.

At the upper part of the base A, at the sides thereof, and of the requisite height or depth, there are two parallel toothed racks R, R, with the teeth of which the two toothed wheels S, S, on the impression roller shaft T, engage. The diameter of the toothed wheels S, S, of the impression roller Q, is preferably greater than the diameter of the impression roller Q. The impression roller Q, is carried upon the shaft T, one end

of which is formed preferably square, in order to receive thereon the crank handle U', Figs. 2, and 3, which on being rotated by the hand of the operator of the machine causes the toothed wheels S, S, and the impression roller to be traversed from end to end of the base A. The impression roller Q, may be fastened rigidly to the shaft T, so that as the shaft T, is rotated, the roller Q, is correspondingly rotated in either direction, or the impression roller Q, may be mounted loosely so as to rotate upon the shaft T by its end bushings O'.

At each end of the base A, are recesses Y, and Y', respectively, as shown at Figs. 1, and 2. In each pair of these recesses there are situated the bearings of the rollers to which the printing ribbon is attached, and by which the printing ribbon is operated as herein-after described. Each ribbon roller is provided with a ratchet wheel d, at one of its ends which is firmly fastened to the axis a, of each ribbon roller, and the frame L, of the carriage at the same side of the machine whereat the ratchet wheel d, is situated, carries pivoted to each bi-furcated arm the pawls e, and f, respectively, as shown at Figs. 1, and 2. When the carriage and impression roller of the machine are moved towards either end of the base A, then either the pawl e, or the pawl f, engages with one or the other of the ratchet wheels d, d, according to the direction in which the carriage and impression roller of the machine are being operated, and since each pawl e, or f, makes contact with one or the other of the ratchet wheels d, before the carriage arrives at the termination of its travel, the further movement of the carriage after the contact of its pawl e, or f, with either of the ratchet wheels d, d, causes the rotation of one or the other of the ratchet wheels d, through a distance corresponding to the distance through which the carriage and impression roller move, after the contact of either pawl e, or f, with its corresponding ratchet wheel is made, and in this manner the printing ribbon g, is wound through a corresponding distance off one of the ribbon carrying rollers, and upon, or on, to the other ribbon carrying roller. By this arrangement a fresh surface of printing ribbon is presented to the type or other printing surface at each traverse of the carriage and impression roller, and anteriorly to making the next succeeding impression or printing operation.

To insure that the requisite length of movement of the ribbon rollers for producing the requisite movement of the ribbon g, shall be capable of adjustment, the pawls e, and f, while carried pivotally upon the pins h, h, rest upon the top surface of the sides of the base A, of one of the guides as shown at Figs. 1, and 2, until reaching the ratchet wheels d, one on the end of each ribbon roller,

when the pawls respectively engage with the ratchet wheels *d*, and rotate them together with each ribbon roller alternately, so as to wind off one of the ribbon rollers and on to the other ribbon roller a length of printing ribbon adequate to supply a fresh surface of such ribbon at each printing operation. The pawls *e*, and *f*, are provided in sets of varying lengths so that they may be changed in the machine according to the varying diameters of the ribbon rollers, and any two of which pawls of different lengths are used simultaneously in the machine, their lengths being such as to correspond with the quantity of ribbon wound off from one roller and wound on to the other printing roller.

Instead of operating the machine hereinbefore described by turning a crank handle *U'*, as described, the machine may be operated by the attendant applying his or her hand to the bridge *M*, of the carriage, and by pushing or pulling the carriage horizontally, causing it and the impression roller to make the successive journeys or traverses upon the base of the machine which have already been described as being performed by turning the crank handle *U'*. When the machine is operated by pushing or pulling the carriage or impression roller, then the crank handle *U'*, may be taken off the axis *T*, of the machine, but it is not necessary to remove the crank handle *U'*, in order to operate the machine by the attendant pushing and pulling upon the bridge *M*.

I desire it to be understood that when using my new or improved machine for printing copies of drawings, maps, landscapes, pictures, etc., or when used for making copies of representations wherein there are not parallel lines, such as the lines of type in type-writing, or the lines in writing in ordinary manuscript, or the lines of engraving, such as is used in the production of public State and National documents, wills, and other papers written by hand, or copies of copper or steel engravings wherein lines of writing or literary signs are placed in parallel, that I do not in such cases use the pawls and ratchets for regulating the motion of the inking ribbon carried upon the inking ribbon rollers of my machine, but instead thereof, when a larger surface is to be printed at each successive impression, or printing operation of a drawing, map, picture or other large continuous surface, that I then remove the pawls from my machine and wind by hand a new surface of inking ribbon of sufficient length corresponding to such surface for each such impression when necessary to be printed from.

In Fig. 4, the inwardly projecting lugs *w*,

w, whereto the plate *x*, when used, is fastened, by means of the adjusting screws and thumb heads *I*, and *I'*, are shown. The corresponding parts being also shown in plan in Fig. 5, while the rest of the parts shown in Fig. 5, correspond with the tightening devices of the furniture and types shown at Fig. 2, and hereinbefore described.

I claim as my invention.

1. A printing machine consisting of a base with grooved parallel sides, an intermittently moving printing ribbon, a carriage movable upon the base carrying an impression roller and provided with upper and lower rollers, 75 the impression roller and its shaft, the lower rollers of the carriage, operating in said grooves in the base, the upper rollers of the carriage operating upon the upper part of the metal of the base containing the grooves, the 80 toothed wheels, one at each end of the shaft which carries the impression roller, the parallel toothed racks at the sides of the upper part of the base, the toothed wheels gearing into the parallel toothed racks, the printing 85 or impression surfaces, the inking ribbon rollers, the ratchet wheels, one on one end of each inking ribbon roller, the changeable pawls on one end of the carriage for operating the inking ribbon rollers, substantially as de- 90 scribed.

2. The combination with the traversing carriage of a printing machine operating upon a flat base and provided with upper and lower rollers, of an impression roller pressing 95 the paper to be printed, upon an intermittently moving inking ribbon, and the inking ribbon to the type and printing surfaces, the toothed racks on the base of the machine, the toothed wheels on the axis of the impression 100 roller, the inking ribbon, the inking ribbon rollers, the ratchet wheels, one on one end of each inking ribbon roller, the changeable pawls on one end of the carriage adapted to operate the ratchet wheels of the inking ribbon rollers, the lower rollers of the carriage operating in grooves in the bottom of the parallel guides of the base of the machine, the parallel guides, the upper rollers in each end of the carriage operating upon the top of 105 the parallel guides of the base of the machine, the type and printing surfaces, the crank handle for operating the machine, all substantially as set forth.

In testimony whereof, I have hereunto set 115 my hand and seal at the city of Los Angeles, aforesaid, in the presence of two subscribing witnesses.

BENJAMIN OTTO FANSLOW. [L. s.]
